UNITED STATES PATENT OFFICE

2,554,977

ELECTRONIC VOLTAGE REGULATOR

William T. Chapin, Schenectady, N. Y., assignor
to General Electric Company, a corporation of
New York

Application March 27, 1946, Serial No. 657,409

1. Claim. (Cl. 321—23)

1

My invention relates to electron tube regulators and more particularly to electron tube-regulators employing a gas discharge device as a source of reference potential.

In accordance with one method of securing regulated unidirectional voltage or other desired controlled quantity the grid bias of a series connected electron discharge device is controlled in accordance with the quantity desired to be maintained constant. In a voltage regulator, for instance, the actual output voltage is compared with a known constant voltage obtained from a gas discharge device or similar constant voltage source and fed back through an amplifier circuit to the controlled device. This degenerative feedback causes the output voltage to remain substantially constant under all conditions of input voltage and load current within the operating range of the system.

In general it has been found particularly convenient to use a gas discharge device as a source of constant reference potential in electron tube regulators. This device has a substantially constant voltage drop over a very wide range of operating current and produces a substantially constant reference voltage over a large range in current flow. The gas discharge device is particularly desirable as compared with batteries or other sources of reference potential because of its small size, low cost, and freedom from deterioration.

In the application of gas discharge devices to electron tube regulators, maximum performance can be achieved if the circuit connections permit operation of the gas discharge device in the optimum portion of its operating characteristic while at the same time allowing other circuit components to operate most effectively. In particular, the gas discharge device should not be located at a point in the circuit where its own voltage drop serves to reduce the cathode-anode potential of an amplifying tube in the feedback path. Otherwise the amplification of that tube will be reduced and the degree of regulation obtained thereby limited. Furthermore, the gas discharge device should be arranged to carry current which is reasonably constant over all conditions of operation of the regulating circuit. In addition it is highly desirable that the gas discharge device be arranged at a point in the circuit where it is not required to carry a large current, particularly a large current which varies in accordance with the operating conditions of the regulator.

In addition to the above considerations in applying a gas discharge device to an electron

5 tube regulator it is essential to arrange the device in a manner which provides a maximum degree of stability. In the region where the voltage drop across an electron discharge device is nearly constant, there are usually points wherein the device presents a negative impedance to the flow of current. That is, under some conditions of operation an increase in current flow through the gas discharge device results in a decrease in voltage drop. At such points, the regulator has an inherent tendency to be unstable in operation and to pass from one condition of operation to another in random fashion. In order to avoid this phenomena it is desirable that the gas discharge device be located in the regulator circuit in a manner which "decouples" this negative resistance characteristic to a maximum degree.

10 It is the object of my invention to provide an improved electronic voltage regulator.

15 It is a further object of my invention to provide a regulator in which the current flow through the source of reference potential is nearly constant over all conditions of operation.

20 Still another object of my invention is to provide a regulator in which current flow through the source of reference potential is very small.

25 Yet another object of my invention is to provide a regulator in which amplifying devices in the feedback path operate at maximum amplification and efficiency under all conditions of operation.

30 It is an additional object of my invention to provide a regulator having a maximum degree of stability.

35 The novel features which I believe to be characteristic of my invention are set forth with particularity in the appended claim. My invention itself, however, both as to its organization and method of operation, together with further objects and advantages thereof, may best be understood by reference to the following disclosure taken in connection with the accompanying drawings in which Fig. 1 illustrates one embodiment of my invention and Fig. 2 is an explanatory diagram relating thereto.

40 Referring now to Fig. 1 which shows a schematic diagram of a voltage regulator embodying the features of my invention, 1 represents a transformer having its primary winding 3 connected to terminals 2 which are connected to a source of alternating voltage. Secondary 4 of transformer 1 supplies filament heating voltage for rectifier device 6 and secondary 5 of transformer 1 supplies anode voltage to the same device. A π section filter comprising smoothing

55

inductor 8 and shunt capacitors 7 and 9 smooths out the rectified voltage of device 6 to provide a relatively smooth voltage across condenser 9. Electron discharge device 11 is connected between the positive terminal of condenser 9 and the positive load terminal 17 to control the relative value of voltage across output terminals 17 and 18 as compared with the voltage across condenser 9. Bias for device 11 is supplied by current flow through resistance 10 and electron discharge device 12. Grid bias for device 12 is supplied from the auxiliary control circuit comprising gas discharge device 15, potentiometer 14, resistance 13, resistance 16, and condenser 19, the operation of which is explained in further detail below.

Considering now the auxiliary control circuit, condenser 19 is periodically charged through rectifier 20 to the full value of voltage across one section of secondary winding 5 of transformer 1. Inasmuch as the capacity of this condenser is made relatively large, the charging action of condenser 19 provides a relatively constant voltage across that condenser which is nearly equal in magnitude to the peak voltage across condenser 7. Hence, the series circuit comprising gas discharge device 15, resistance 16, and condenser 19 may be regarded as including two sources of voltage (device 15 and condenser 19) and a series resistance (resistance 16) connected across the voltage developed between terminals 17 and 18. Inasmuch as the voltage across device 15 may be regarded as constant, current flow must take place through resistance 16 to cause the voltage difference between the negative terminal of device 15 and the negative load terminal 18 to equal the difference between these two voltages. Designating the load voltage as e_0 and the voltage of device 15 as e_r , the total grid bias applied to device 12 then becomes:

$$(1) \quad E_g = e_0 - e_r + k e_r$$

Where:

E_g is the applied grid bias.
 k is the portion of the voltage across device 15 between the roving terminal of potentiometer 14 and the negative terminal of device 15.

Or:

$$(2) \quad E_g = e_0 + (k-1) e_r$$

Since the value of k is always less than one, the term $1-k$ will always be positive and can be regarded as a new constant K . Then:

$$(3) \quad E_g = e_0 - K e_r$$

Hence the grid voltage applied to device 12 is proportional to the difference between the regulator output voltage and a selected portion of the voltage across electron discharge device 15, the value of the selected portion being determined by the setting of potentiometer 14.

Operation of the circuit of Fig. 1 is based on the principle of inverse feedback with respect to the difference between the voltage across terminals 17 and 18 and a selected portion of the voltage across gas discharge device 15. It is well known that a high degree of amplification in the feedback path will reduce this voltage difference substantially to zero even though the applied voltage at terminals 2 and the impedance across terminals 17 and 18 are changed. In the circuit of Fig. 1, this high degree of amplification is provided by electron discharge device 12 acting in conjunction with resistance 10 to control the effective internal resistance of electron discharge

device 11. With the circuit of the figure, these components may be chosen to provide a maximum degree of amplification for in practical regulator applications the voltage across condenser 9 will not vary over a large range. The relatively constant voltage drop across gas discharge device 15 does not reduce the effective anode voltage at device 12 because device 15 is located in an entirely separate circuit where it does not influence device 12.

Further features of my invention will now be explained with reference to Fig. 2 which shows a modified equivalent schematic diagram of a portion of the circuit of Fig. 1. In Fig. 2 battery 21 indicates schematically the constant voltage which appears across condenser 19. Inasmuch as rectifier 20, Fig. 1, is connected to charge condenser 19 in a manner causing the condenser electrode connected to terminal 18 to be positive, battery 21 is shown as having its negative terminal at point a . For purposes of illustration, the peak potential appearing across half of the secondary winding 5 of transformer 1 is shown as 400 volts, thereby causing point a to have a potential of 400 volts negative with respect to the potential of terminal 18. This voltage also appears across condenser 7 but the voltage drops across inductor 8 and device 11 reduce the voltage at terminals 17 and 18 to a lower value. For purposes of illustration, this value is taken as 300 volts. Preferably a gas discharge device 15 is employed which provides a voltage drop which is greater than the voltage across terminals 17 and 18. In the voltage regulator herein described, for instance, a device giving 400 volts drop, may be used thereby causing point b to be 400 volts negative with respect to terminal 17 or 100 volts negative with respect to the potential of terminal 18.

The above described regulating circuit has a number of advantages. In particular, the grid of device 12 can be maintained at a negative potential relative to the cathode over any desired voltage range by properly proportioning the values of the circuit components. This prevents flow of grid current in device 12, thereby enabling it to operate in the most effective region of its characteristics and at a point where overheating will not occur. Furthermore, variation in output voltage across terminals 17 and 18 has a reduced effect on current flow through device 15 by reason of the auxiliary voltage source 21. If, for instance, potentiometer 14 is adjusted to provide output voltage across terminals 17 and 18 of 150 volts the total effective voltage acting in the circuit comprising device 15, resistance 16, and voltage source 21, is 400+150 or 550 volts. This represents about 80 per cent of the 700 volts applied to this circuit for 300 volts output. Obviously, greater voltage at source 21 provides an even smaller change in voltage across this circuit when load voltage is varied.

Inasmuch as the value of grid voltage applied to device 12 is proportional to the difference between a pre-selected portion of the voltage across gas discharge device 15 and the output voltage across terminals 17 and 18, the exact value of voltage at source 21, Fig. 2, does not influence regulator performance. Hence, this voltage may be obtained from an unregulated source, such as transformer 1, Fig. 1, without influencing performance of the regulator.

While I have described herein the application of my invention to a voltage regulator, it will be apparent to those skilled in the art that it may be applied to other regulators as well. If, for

instance, it is desired to maintain the speed of a direct current motor constant, the circuit comprising device 15, potentiometer 14, resistance 16 and condenser 19, may be connected directly across the motor terminals. This will cause the regulator to maintain substantially constant the counter-electromotive force of the motor and hence regulate the motor speed. In a similar manner the circuit may be applied to maintain constant load current or other load quantity which may be represented by a voltage capable of actuating the control circuit.

While I illustrated and described a particular embodiment of my invention, it will of course be understood that I do not wish to be limited thereto since various modifications both in the circuit arrangement and the instrumentalities employed may be made, and I contemplate by the appended claim to cover any such modifications as fall within the true spirit and scope of my invention.

What I claim as new and desire to secure by Letters Patent of the United States is:

A regulated power supply system comprising, in combination, a transformer adapted to be energized from an alternating voltage and having a secondary winding, a load circuit energized from said secondary winding and serially consisting of a rectifier and the anode-cathode path of a grid-controlled discharge device and a load device, a second grid-controlled discharge device having its anode-cathode path connected across said load device and said first device, means for varying the grid voltage of said first device in accordance with the space current in said second

device, a control circuit connected directly across said load device and responsive to the load voltage, said control circuit serially including a potentiometer, a series regulating resistor and a capacitor, means comprising a voltage-stabilizing glow discharge device connected directly across said potentiometer for maintaining a constant voltage thereacross, the grid of said second tube being connected to an adjustable tap point on said potentiometer, and means comprising a second rectifier energized from said transformer for independently charging said capacitor to a voltage proportional to the voltage across said secondary winding, the polarity of said last voltage being such as to aid the flow of current through said regulating resistor due to the load voltage, the resultant variations in the grid voltage of said first device being in polarity to minimize variations in said load voltage.
